UNITED STATES PATENT OFFICE.

WILLIAM U. GRIFFITHS, OF PHILADELPHIA, PENNSYLVANIA.

VALVE-CONTROLLING MEANS FOR FLUSH-TANKS.

1,302,154.

Specification of Letters Patent. Patented Apr. 29, 1919.

Application filed October 25, 1916. Serial No. 127,548.

To all whom it may concern:

Be it known that I, WILLIAM U. GRIFFITHS, a citizen of the United States, and a resident of the city of Philadelphia, county 5 of Philadelphia, State of Pennsylvania, have invented certain new and useful Improvements in Valve-Controlling Means for Flush-Tanks, of which the following is a specification.

- 10 One of the principal objects of my invention is to provide means whereby the valve for closing the outlet port of a flush tank may be held more tightly closed than is now the case as far as I am aware.
- 15 A further object of my invention is to provide means whereby a force, other than that due to the weight of the valve and parts associated therewith, may be applied to the said valve or to a part connected 20 therewith to exert an additional pressure or force upon the said valve to hold it normally tightly and closely shut.

A further object of my invention is to provide means whereby a relatively small 25 weight may be caused to exert a relatively great force upon the valve closing the port opening into a flush pipe leading from the water tank to the part which is desired to flush with water from said tank.

30 Other objects and advantages of my invention will be hereinafter pointed out in the detailed description of my invention which follows or will be apparent from such description.

35 In order that my invention may be more readily understood and its practical advantages more fully appreciated reference should be had to the accompanying drawings in which I have illustrated one form 40 of a convenient embodiment thereof. It will be understood, however, that changes in the details of construction may be made within the scope of the claims without departing from my invention.

45 In the drawings:—

Figure 1 is a view in side elevation of mechanism embodying my invention and also showing portions of the flush tank in section and the outline of two sides of the 50 flush tank and the water therein being indicated by dash and dot lines; and

Fig. 2 is a sectional view taken on the line 2—2 of Fig. 1.

Referring to the drawings, 1 designates 55 the bottom of a flush tank to which water is supplied through a pipe 2. The flow of

water through said pipe is controlled by a valve 3, the latter being controlled by means of a pivoted cam acting member 4, actuated by the rise and fall of a float 5. The rising 60 and falling of the float 5 is occasioned by the rising and falling of the water 6 within the flush tank in known manner. When the float 5 is in the position shown in Fig. 1 of the drawings the valve 3 is in closed position 65 and is permitted to open under the influence of the pressure of the water in the pipe 2, as the float 5 falls or moves toward the bottom 1 of the flush tank.

Normally the water in the flush tank is 70 in the position indicated in Fig. 1.

10 designates a short section of pipe which is adapted to be connected with a flush pipe (not shown) having connection with the part to be flushed, as for instance, a water 75 closet bowl. Normally the upper end of said pipe or other port through which the water is adapted to be discharged from the tank is closed by means of a valve 11 pivotally supported at 12 upon a lever 12^a pivot- 80 ed at 13. The outer swinging end of the lever 12^a is provided with a float 14 the buoyancy of which, when acted upon by water in the tank, tends to lift the valve 11 to open the port. Normally however up- 85 ward movement of the float 14 is prevented by the action of a weight 17, the said weight being supported upon the outer end portion of an angular arm or member 18, pivoted at 19 upon a bracket 20 projecting upwardly 90 from an upper end portion of the section of pipe 10.

When the lever 12^a is in a substantially horizontal position, as shown in the drawing with the valve 11 in closed position, the arm 95 18 extends transversely of the said lever and is in contact with and bears upon the same, as shown very clearly in Fig. 2 of the drawings. The point upon the arm 18 which is in contact with the lever 12^a is relatively 100 near the pivotal point 19 of the said arm.

When it is desired to open the valve 11, the same is lifted in known manner by the action of a crank 21 through a link 21', the latter having connection at its upper end 105 with the said crank and at its lower end with the lever 12^a. Upon turning the crank 21 into the position indicated in dotted lines in Fig. 1 of the drawing, the valve 11, lever 12^a and float 14 are lifted upwardly into the 110 position indicated by dotted lines in Fig. 1.

The arm 18 is provided with a portion

which occupies a substantially horizontal position when the lever 12^a is in its lowermost position to close the valve 11, as shown in Fig. 1 and also with the portion 22 extending downwardly substantially at right angles to the horizontal portion. These two portions are connected by means of a diagonally extending cam acting portion 23. The outer end of the portion 22 is bent and inclined inwardly as indicated at 24 and constitutes a stop to limit the upward movement of the lever 12^a. The weight 17 is supported upon the portion 22 of the arm 18.

When the arm 12^a is lifted by the crank 20 and link 21 it causes an upward swinging movement of the arm 18 and by reason of the presence of the cam acting portion 22 the arm 18 is thrown and moved to a position so as to transfer the line of the center of gravity of the combined weight of said arm and the weight 17 from the right hand to the left hand side of the pivot 19. The movement of the arm toward the left is limited by the contact thereof with the stop 26 upon the upper end of the bracket 20. As soon as the lever 12^a is lifted to open the valve 11 the water begins to flow through the outlet port into the flush pipe. The buoyancy of the float 14 is sufficient to support the lever 12^a in position to hold the valve 11 open, but as the water in the tank falls the float 14 falls until finally the lever 12^a strikes the projection 27 which occupies the position shown in dotted lines in Fig. 2 when the arm 18 is in the dotted position shown in that figure. The weight of the valve 11, lever 12^a and the float 14 upon the said projection 27 is sufficient to cause pivotal movement of the arm 18 toward the right to carry the same into position so that the line of gravity of the combined weight thereof and of the weight 17 is moved to the right hand side of the pivot 19, after which the said arm under the influence of its own weight and that of the weight 17 falls into the position shown in full lines in Fig. 2 and operates to hold the lever 12^a in depressed position with the valve 11, tightly closed, notwithstanding the tendency to move upward under the influence of the buoyant action of the float 14, as the water rises in the tank.

At the time the water in the tank has fallen so that the valve 11 is about to close, the valve 3 is open, so that the water is flowing with full force into the tank. The rapid inflow of water into the tank at this time maintains the water in the tank at a height sufficient to act upon the float 14 to prevent the valve 11 from seating closely against its seat. In other words, the valve is held partially open or is "cracked" so that the water continues to flow through the outlet port and the tank does not fill. When a device embodying my invention is employed it oper-

ates as above described to close tightly the valve for the outlet port and thus avoids the difficulty just referred to.

I claim:—

1. In combination, a pivotally swinging valve for closing a port, a pivoted device adapted to contact with a portion of the valve structure for holding the valve in closed position when once closed, the said device swinging in a plane extending transversely of the plane in which the said valve swings, and the said device being lifted by contact therewith of a portion of said valve structure when the latter is lifted to open the said valve. 70

2. In combination, a pivotally movable valve structure for closing a port of a flush tank, means for opening and closing the said valve structure, and means extending transversely of the plane of movement of and contacting with the said valve structure for holding the same in closed position when once closed, and the said valve structure when lifted to open position acting upon said means to lift the same. 80

3. In combination, a pivoted valve structure for closing a port, said valve structure moving in a vertical plane, means for causing movement of said valve structure to open and close said port, and a pivoted device adapted to fall upon said valve structure as it moves toward its closed position to cause a sudden closing movement of the same and to exert pressure upon the same to hold it in tightly closed position after it 95 has once been closed.

4. In combination, a pivotal swinging valve for closing a port, a pivoted device adapted to contact with a portion of the valve structure for holding the valve in closed position when once closed, the said device swinging in a plane extending transversely of the plane in which the said valve swings, and the said device being lifted by contact therewith of a portion of said valve structure when the latter is lifted to open the said valve, said device being provided with means at its outer end for contacting with a portion of the said valve structure for limiting the opening movement thereof. 110

5. In combination, a lever pivoted at one end, a valve pivotally supported upon said lever intermediate its ends which valve is adapted to close a port of a flush tank, a buoyant device supported upon the outer swinging end of said lever, means for lifting the said lever to open the said valve and to permit a flow of water from the said tank through the said port, an arm pivotally supported adjacent to said lever and swinging in a plane transversely of said lever and normally resting upon said lever said arm being adapted to be lifted and swung about its pivot by the upward movement of the said lever and the said arm being provided 120

125

130

with means which is adapted to be contacted with by the said lever as the latter falls to close the said valve, the weight of the said lever, the said valve and the said buoyant 5 means causing movement of the said arm about its pivot in the position to again rest upon the said lever.

6. In combination, a lever pivoted at one end, a valve pivotally supported upon said 10 lever at a point intermediate its ends and adapted to close an outlet port of a flush tank, a buoyant device having connection with said lever and tending to move said valve into open position, a weighted device 15 pivotally supported adjacent to said lever and normally resting upon the same to prevent upward movement thereof and means for lifting the said lever to open the said valve, such movement of said lever causing 20 an upward swinging movement of the said weighted device, substantially as described.

7. In combination, a lever pivoted at one end, a valve connected with said lever at a point intermediate its ends and adapted to 25 close an outlet port of a flush tank, a buoyant member carried upon the outer end of said lever, said member tending to move upwardly under the influence of water in the said tank, an arm pivotally supported adjacent to the said lever, the pivot of said arm being substantially parallel with the adjacent portion of said lever, a weight carried 30 upon said arm, the said arm normally ex-

tending across and resting upon the said lever to hold the same in depressed position, 35 means for lifting the said lever to open the said valve and to cause a swinging movement of said arm about its pivot to transfer the line of the center of gravity of the combined weight of the said arm and the weight carried thereby to the opposite side of the pivot thereof from that occupied by the said lever, the said arm having means for limiting the upward movement of the said lever and the said arm also having means whereby the 45 said lever as it descends causes pivotal movement of the said arm into its normal position transversely of and in contact with said lever.

8. In combination, a pivoted member, a 50 valve secured to said member, said valve being adapted to open and close a port, a pivotally supported arm provided with a weight a distance from its pivot, said arm swinging 55 in a plane at right angles to the said pivoted member and the said arm being adapted to rest upon the said member, when the latter is in its lowermost position with the valve secured thereto closing said port, to hold the said valve tightly closed and means for lifting the said member to open the said valve. 60

In testimony that I claim the foregoing as my invention, I have hereunto signed my name this 23rd day of October, A. D. 1916.

WILLIAM U. GRIFFITHS.
